BOILER

Howard J. Kerr, Westfield, N. J., and Ivar L. Langvand, Barberton, Ohio, assignors to The Babcock & Wilcox Company, Bayonne, N. J., a corporation of New Jersey

Application December 26, 1928, Serial No. 328,570

6 Claims. (Cl. 122—302)

This invention relates to a novel and improved form of boiler, particularly of the Stirling type, and will be best understood from the following description. In the accompanying drawings, in which there are shown selected embodiments of the invention,

Fig. 1 is a vertical sectional view through a Stirling boiler constructed according to the invention.

Fig. 2 is a section on the line 2—2 of Fig. 1.

Fig. 3 is an enlarged detailed view adjacent the steam outlet shown in Fig. 1.

Fig. 4 is a view corresponding to Fig. 1, but showing a different form of the invention.

Fig. 5 is an enlarged view showing the arrangement of baffles adjacent the steam outlet in Fig. 4.

Referring first to Figs. 1, 2 and 3, the invention is shown as embodied in a boiler disposed above a combustion chamber 1 to which heat is supplied from a suitable source exemplified by a grate 2 beneath a combustion arch 3. The boiler comprises a lower water drum 4, and upper front, middle and rear steam and water drums 5, 6 and 7 respectively. The upper drums are connected to the lower drum by banks of tubes. The bank 8 connects the lower drum to the upper drum, while the bank 9 is split, some tubes entering the front drum 5 and others the middle drum 6, and the rear bank 10 is likewise split with some of the tubes entering the middle drum 6 and some the rear drum 7.

Suitable means in the form of baffling is provided to form a plurality of passes, each including one of the aforesaid banks of tubes. The particular form of baffling, in itself, forms no part of this invention, and therefore will not be described in detail. It is sufficient, for the purposes of this invention, that this baffling should form the plurality of passes referred to above, in which are disposed tubes leading to two drums instead of one at the top ends.

From this arrangement of baffling, it will be seen that the tubes connecting the lower drum to each of the front and middle upper drums are disposed some in a relatively hot pass, and some in a relatively cool pass, the hot gases from the combustion chamber being cooled by the bank of tubes 8 before they reach the pass in which the second bank 9 is disposed. Similarly, these gases are cooled by the tubes 9 before they reach the tubes 10 in the next pass. The gases may then pass out through the flue 11.

In the form shown, preferably the sole connection between the drums below the normal water lines therein is formed by means of the above described tubes and the water drum. For example, the only connection below the water levels in the drums 5 and 6 is furnished by means of the tubes in the bank 9 and the water drum 4. In other words, the usual water circulators

between upper drums have been omitted, and water in an upper drum returns to the steam making tubes by passing directly to the water drum without passing through another top drum.

In this form, the rear drum is provided with a steam outlet 12, and each of the drums 5 and 6 is connected directly to the drums 7 by steam circulators 13 and 14 respectively. These circulators form the sole connections between the drum, above the normal water levels therein. The middle drum 6 is provided with a gauge glass 6' to indicate the water level therein, and feed water is supplied to the rear drum 7 at an inlet 15. Suitable baffling 16 is disposed in the drum 7 between the outlet and the steam circulators 13 and 14. This baffling is shown as being supported on the end of the outlet pipe by means of straps 17.

In operation, steam will be generated in the water tubes and mixed steam and water will be carried upwardly into the steam and water drums. The normal level of water in the middle drum is indicated by the line 18, and this level will be indicated approximately on the glass 6'. In normal operation, the levels in the drums 5 and 7 should approximate the levels indicated by the lines 19 and 20, but various causes may result in the levels more nearly approximating those indicated by the lines 21 and 22 respectively. It has been found that by the novel arrangement of circulators and tubes described above, the level in the rear or steam outlet drum is maintained sufficiently low to greatly decrease the danger of priming. Moreover, the arrangement of circulators 13 provides a smooth even support for the roof 23 of the boiler casing.

Referring now to Figs. 4 and 5, there is shown therein a boiler of the same type as shown in Fig. 1, and to which similar numerals have in large part been applied. The numerated parts 40 will not be described again. In this form, however, the steam outlet 12' is arranged on the middle drum 6 and suitable baffling is arranged within this drum between the circulator 14 and the outlet 12'. In this form the rear drum 7 45 acts as a separator for any moisture in the steam which is discharged thereinto through the steam circulators 13. In Fig. 4, the various water levels are indicated by the same numerals as in Fig. 1. It is to be understood that these levels are only 50 approximate.

Referring to Fig. 5, it will be seen that there is provided a plurality of baffles 24, 25 and 26, providing a tortuous path for the steam to follow from the circulators 14 to the outlet.

While there have been shown certain embodiments of the invention, it is to be understood that other forms may be devised which come within the scope of the invention as defined in the appended claims.

We claim:—

1. In a water tube steam boiler, a boiler setting, a middle steam and water drum located between two similar drums at the top of the setting, tubes leading from said drums to a lower water chamber, primary baffles dividing the tubes into a plurality of separated banks located in separate gas passes extending through the setting, a lower number of tubes in a bank leading to a drum 10 from which a greater number of tubes extend downwardly through an adjacent gas pass of higher temperature, the tubes in a bank being bent at their upper ends so as to constitute diverging groups of tubes, secondary baffles located 15 between adjacent upper drums and between said diverging groups of tubes, said secondary baffles forming gas pass walls guiding the furnace gases at their turns, a steam off-take connection communicating with the steam space of one of the upper drums, one of the upper drums having no steam circulators directly connecting it with one of the other upper drums, and steam circulators connecting the steam spaces of two of the upper drums, the only water circulator connections between the upper drums being through said 20 groups of tubes which provide recirculation in the upper drums.
2. In a water tube steam boiler, a boiler setting, a middle steam and water drum located between two similar drums at the top of the setting, tubes leading from said drums to a lower water chamber, baffles dividing the tubes into a plurality of separated banks located in separate gas passes extending through the setting, a lesser number of the tubes in a bank leading to a drum 25 from which a greater number of tubes extend downwardly through an adjacent gas pass of higher temperature, the tubes in a bank being bent at their upper ends so as to constitute diverging groups of tubes, secondary baffles between adjacent upper drums and having diverging portions extending along diverging tubes of said diverging groups of tubes, said secondary baffles forming gas pass walls guiding the furnace gases at their turns, a steam off-take connection communicating with the steam space of one of the upper drums, one of the upper drums having neither steam nor water circulators directly connecting it with one of the other upper 30 drums, and steam circulators connecting the steam spaces of two of the upper drums and extending over the middle drum and having no direct connection therewith, the only water circulator connections between the upper drums being through said groups of tubes which provide recirculation in the upper drums.
3. In a water tube steam boiler, a boiler setting, a middle steam and water drum located between two similar drums at the top of the setting, tubes leading from said drums to a lower water chamber, primary baffles dividing the tubes into a plurality of separated banks located in separate gas passes extending through the setting, a lower number of the tubes in a bank leading to a drum from which a greater number of tubes extend downwardly through an adjacent gas pass of higher temperature, the tubes in a bank being bent at their upper ends so as to constitute diverging groups of tubes, secondary baffles located between adjacent upper drums and above said diverging groups of tubes, said secondary baffles forming gas pass walls guiding the furnace gases at their turns, a steam off- 40

take connection communicating with the steam space of one of the upper drums, one of the upper drums having no steam circulators directly connecting it with one of the other upper drums, and steam circulators connecting the steam spaces of two of the upper drums, the only water circulator connections between the upper drums being through said groups of tubes which provide recirculation in the upper drums.

4. In a steam boiler of the Stirling type, a steam off-take drum, a rear drum, a front drum, first steam circulators extending from the steam space of the front drum over the off-take drum to the rear drum and constituting the only direct connection between the front and rear drums, second steam circulators extending from the steam space of the rear drum to the off-take drum and constituting the only means connected to the steam space of the off-take drum delivering steam thereto directly from another drum, a water drum, a furnace, baffles providing a plurality of gas passes, a first set of tubes connecting the front drum and the water drum, a second set of tubes directly connecting the rear drum and the water drum and extending through one gas pass to constitute the only circulatory means connected to the water space of the rear drum, a third set of tubes connected directly to the off-take and water drums and divided so that more of its tubes are in a gas pass of a temperature higher than the gas pass in which its remaining tubes are located, and steam and water separation baffles in the steam space of the off-take drum and located in the path of mixture discharge from the tops of the third set 20 of tubes.

5. In a steam boiler of the Stirling type, three upper steam and water drums including a rear steam off-take drum, a water drum below the steam and water drums, banks of tubes directly connecting the water drum to the upper drums, steam circulators extending past the middle upper drum and directly connecting the front and rear upper drums, other steam circulators directly connecting the middle upper drum to the rear drum and constituting the only direct connection between those drums, a steam offtake connection leading from the rear upper drum, and a feed water connection to the offtake drum delivering feed water thereto so that it may freely contact with such circulating boiler water as enters the off-take drum, the lower drum constituting an unobstructed mixing chamber.

6. In a steam boiler of the Stirling type, three upper steam and water drums including a rear steam offtake-drum, a water drum below the steam and water drums, groups of tubes each directly connecting an upper drum with the water drum, gas pass boundary baffles dividing groups of the tubes, steam circulators extending over the middle upper drum and directly connecting the front and rear upper drums, other steam circulators directly connecting the middle upper drum to the rear drum and constituting the only direct connection between those drums, a steam offtake connection leading from the rear upper drum, and a feed water connection to the offtake drum delivering feed water thereto in contact with such circulating boiler water as enters the off-take drum, the lower drum 60 constituting an unobstructed mixing chamber.

HOWARD J. KERR.
